UNITED STATES PATENT OFFICE.

BELVIN T. WILLISTON, OF SOMERVILLE, MASSACHUSETTS, ASSIGNOR TO THE UNITED INJECTOR COMPANY, OF NEW YORK, N. Y., A CORPORATION OF NEW YORK.

COMPOUND VALVE.

1,119,381.

Specification of Letters Patent.

Patented Dec. 1, 1914.

Application filed March 2, 1914. Serial No. 821,938.

To all whom it may concern:

Be it known that I, BELVIN T. WILLISTON, citizen of the United States, and resident of Somerville, in the county of Middlesex and State of Massachusetts, have invented new and useful Improvements in Compound Valves, of which the following is a specification.

My invention consists in a new and improved compound valve, adapted to seat accurately and effectively over two ports which are fixed with relation to each other, except for variations due to expansion of the metal body in which such ports are formed.

Heretofore the generally accepted mode of closing two such ports by a single valve structure has been to make one or both of the valves as a piston valve; usually one valve member has been a seating valve and the other a piston valve.

One of my objects is to provide a valve with two members, both of which close by seating, which will effectively close two relatively fixed ports, in spite of inequalities produced by thermal expansion, and wear.

My improved valve is intended especially for boiler feeding injectors, of which the Hancock inspirator is a type, and in which a single valve control distributes the steam and times the operation of lifter tubes, force tubes, and overflow valve. I therefore describe my improved valve in connection with such an injector.

In the drawings which illustrate my invention,—Figure 1 shows a boiler feeding injector of the double tube type, in longitudinal section; and Fig. 2 shows on an enlarged scale, partly in side elevation and partly in section, a compound valve embodying my invention.

In Fig. 1 the compound valve is shown at V, N, N⁶, V and N⁶ being the principal valve members while N generally designates the valve carrier. S is the valve controlling stem, and P a secondary valve, movable, though confined in, the carrier N of the compound valve. 1 represents the steam supply passage, 2 the water supply, E the lifter tubes and F the force tubes, of the injector. C' and C⁴ are the seats, respectively, for the valve members N⁶ and V. C represents the casing generally. In injectors of this type as heretofore manufactured, the rear valve member of the compound steam valve has been seated over its port, as in the

present valve, but the forward valve member has been a piston valve, fitting within a cylindrical port. The secondary valve, corresponding in function to the secondary valve P of these drawings has heretofore not been completely satisfactory because it has been held to the valve stem by a one-sided engagement. Wear due to vibration has rendered the valve of this old style imperfect after varying periods of use, particularly at the forward end, where the piston valve is located. A full description of a valve of this character will be found in United States Patent No. 492,944 issued to William R. Park and myself on March 7, 1893.

Referring now to Fig. 2: N represents generally the carrier for the compound valve, one member of which N⁶ is a flange integral with the carrier, the other member 75 being the valve V, at the forward end of the carrier and slidably mounted thereon, by means of the screw stem T, shouldered at T', threaded at T² and swaged steam tight at V⁴, said stem sliding in the bored-out 80 head N¹⁰ of the carrier N. Valve member N⁶ brings its seating face N⁷ to bear on the seat C', which is formed in the casing, while valve member V brings its face V² to bear on the seat C³, also on the casing. When 85 valve member N⁶ is seated, steam pressure at the back of member V holds its face V² to its seat C³. The forward end of the valve member V is, roughly speaking, conical in shape except for the narrow cylindrical portion V³ which fits loosely in the port formed by the cylindrical opening in the casing at C⁴. The valve member V, as above stated, is susceptible of a limited sliding movement 90 on the valve carrier N by reason of its manner of mounting which is as follows: The carrier N, which comprises sliding guide members N⁸, terminates in a cylindrically perforated head N¹⁰ situated at the juncture of the inclined converging arms N⁹. A 100 screw T, the cylindrical shank of which enters the bore of the head N¹⁰ with a free sliding fit, is screwed into a correspondingly threaded hole T² in the valve member V, the shoulder T' bringing up firmly against the rear side of the valve member V. The valve member V is rolled or swaged over the threaded portion of the screw T at V⁴ so that the valve member V is securely and inseparably joined to the valve carrier N, with 105 110

freedom to slide within the limits permitted by the dimensions of the screw T and head N¹⁰.

When the valve carrier N is moved forward 5 the loosely mounted valve member V enters the port C⁴ and thereupon the steam pressure acting at the rear of the valve member V carries it toward and finally to a seat upon the seating surface C³ formed in the 10 casing; this seating of the valve member V will therefore under normal conditions just precede the seating of the valve member N⁶, which is positively brought to its seat at C¹ by the forward movement of the stem S. 15 By thus arranging the two valve members V and N⁶ so that within a suitable range their movements are mutually independent, the two valve members will seat accurately and tightly without reference to such changes 20 in relative position of the valve seats as may be due to variations in temperature or unequal wear. Both valve members are, strictly speaking, seating valves as distinguished from piston valves, so that no reliance is placed upon the fitting of a piston 25 valve with its aperture, a mode of closure which is peculiarly susceptible to deterioration in accuracy. The valve member V can sustain considerable wear without losing its 30 capacity for accurate steam tight seating and can easily be reground to a seat, like any seating valve, whenever this may be found necessary.

In order to insure smoothness of action in 35 the compound valve herein described, I have contrived and adopted the construction of the secondary valve P shown in Fig. 2. This secondary valve seats over the port opening L in the valve carrier N and controls 40 this port and also the smaller ports provided with perforations N⁴ which are drilled radially through the side of the valve carrier N terminating in the annular recess N³. The secondary valve P is centrally recessed as P' to receive the forward end of 45 the stem S; this recess P' lies at the bottom of a larger recess which is threaded to receive a threaded thimble Q. This threaded thimble Q is made to engage the stem S 50 with a sliding fit. Near the forward end of the stem S an annular groove is formed at S', this annular groove leaving the stem S with a disk-shaped head S². The thimble Q is recessed at its forward end at Q' to admit 55 the divided ring R, the two parts of which fit fairly closely upon the reduced portion of the stem S, the outer diameter of the divided ring R, R' being such that its two parts fit into the recess Q'. In assembling 60 the secondary valve P, first the cap M which is recessed at M' is slipped over the stem S and after it the thimble Q. The two portions R, R', forming the divided ring, are 65 then placed around the reduced part of the stem S at S' and the thimble Q slid forward

so as to contain the divided ring R, R' within the recess Q. Then the secondary valve P is screwed on to the thimble Q until the divided ring R, R' is pinched between the thimble Q and the inner surface P² of the secondary 70 valve member P. This assemblage leaves the stem S in the recess P' with very little play to move therein, enough however being preferably allowed so that the secondary valve P may not be too rigidly attached to 75 the stem S. Finally, the cap M is screwed into the threaded end M' of the valve carrier N, the flange M² of the said cap surrounding the rear end of the thimble Q. By this mode of assembly the thrust and pull of the stem S on the secondary valve P is evenly distributed 80 and no opportunity is given for any chatter, which in constructions heretofore employed has taken place to such an extent as to wear the surfaces of the compound 85 valve unduly. The secondary valve P slides with a fairly snug fit on the cylindrical inner surface N² of the rearward projection N' of the valve carrier N, and comes to a 90 seat on the surface N⁵.

The operation of the above described compound valve is in general, the same as that of the compound valves heretofore employed in boiler feeding injectors of the type represented by the Hancock inspirator. Initial 95 rearward movement of the stem S lifts the secondary valve P from its seat N⁵ permitting steam to pass through the radial ports N⁴, the central port L and thence to the appropriate steam tubes. Further movement 100 of the stem S draws the secondary valve P still further back until the thimble Q brings up against the rear wall of the chamber formed by the hollow cylindrical end N' of the carrier N and the casing cap M. Additional further movement starts valve member N⁶ from its seat to admit steam in 105 greater volume than before into the space between the seating surfaces C' and C³, the valve carrier N sliding in the bearing formed 110 at C². Finally, the forward end of the carrier N comes to a bearing upon the head of the screw T and lifts the valve member V from its seat at C³ to admit steam through the port at C⁴. 115

Since the stem head S² bears evenly around the divided ring R, the draft of the stem upon the secondary valve P and through it upon the valve carrier N is symmetrically distributed and applied so that the movement of all these parts is smooth and free from chatter whether the compound valve is being opened or closed. Consequently, the valve member V enters the port at C⁴ quietly and smoothly to find its seat in advance of the seating of the valve member, as hereinabove described.

I claim:

1. The combination, with two relatively fixed valve seats, of a compound valve com- 130

prising a valve carrier, one valve member fixed with relation to the valve carrier, the other movably mounted on the valve carrier, and means to move the carrier toward and from the said valve seats, the two valve members adapted to seat on the respective relatively fixed valve seats.

2. The combination, with two relatively fixed valve seats, of a compound valve comprising a valve carrier, one valve member fixed with relation to the valve carrier, the other valve member provided with a stem, said stem mounted to slide in the valve carrier, and means to move the carrier toward and from the said valve seats, the two valve members adapted to seat on the respective relatively fixed valve seats.

3. The combination, with two relatively fixed valve seats in axial alinement with each other, of a compound valve comprising a valve carrier, one valve member at the rear end of said carrier and fixed with relation thereto, another valve member at the forward end of the carrier mounted in sliding relation thereto with limited range of movement thereon, means to move the carrier toward and from the said valve seats, the two valve members adapted to seat on the respective relatively fixed valve seats.

30 4. In a compound valve, for seating over two relatively fixed ports, the combination of a valve carrier, two primary valves to cooperate with relatively fixed seats, one fixed

with relation to the carrier and the other movably mounted on the valve carrier, and 35 a secondary valve mounted and movable to a limited extent in the valve carrier, ports in said valve carrier controlled by the secondary valve, and means to move the secondary valve, and through the medium of the secondary valve to move the valve carrier and the primary valves.

5. In a compound valve, for seating over two relatively fixed ports, the combination of a valve carrier, two primary valves to 40 cooperate with relatively fixed seats, one fixed with relation to the carrier and the other movably mounted on the valve carrier, a secondary valve mounted and movable to a limited extent in the valve carrier, ports in 45 said valve carrier controlled by the secondary valve, said secondary valve comprising a cylindrical shell, threaded to receive a threaded thimble, and valve-operating means comprising the thimble, threaded into 50 the secondary valve shell, a valve stem, annularly grooved, and a divided ring in said groove, clamped between the thimble and secondary valve shell.

Signed by me at Boston, Massachusetts, 55 this twenty-fifth day of February, 1913.

BELVIN T. WILLISTON.
